STUDIO PHOTOGRAPHIC LAMP

James T. Aneshansley, 12 St. James Place,
Brooklyn, N.Y.

Filed June 25, 1962, Ser. No. 70,674

Term of patent 14 years

(Cl. D61—1)

FIG. 4.

FIG. 5.

FIG. 6.

FIGURE 1 is a front perspective view of the studio photographic lamp in accordance with the invention, the lamp head being directed towards the left.

FIGURE 2 is a front elevational view thereof.

FIGURE 3 is a side elevational view thereof.

FIGURE 4 is a rear elevational view thereof showing the side opposite that seen in FIGURE 2.

FIGURE 5 is a side elevational view showing the side opposite that shown in FIGURE 3.

FIGURE 6 is a top plane view thereof.

I claim:

The ornamental design for studio photographic lamp, as shown.
